ALEXANDER FRANKLIN SHREVE, OF HOISINGTON, KANSAS, ASSIGNOR OF ONE-HALF
TO GILBERT SETTE, OF HOISINGTON, KANSAS.

AUTOMATIC MUD-DRUM FOR BOILERS.

1,075,162.

Specification of Letters Patent.

Patented Oct. 7, 1913.

Application filed May 6, 1913. Serial No. 765,776.

To all whom it may concern:

Be it known that I, ALEXANDER F. SHREVE, a citizen of the United States, and a resident of Hoisington, in the county of Barton 5 and State of Kansas, have made certain new and useful Improvements in Automatic Mud-Drums for Boilers, of which the following is a specification.

My invention relates to mud drums for 10 boilers, my particular purpose being to provide a mud drum so constructed and arranged as to be automatic in the sense that it operates continuously and positively in the removal of mud or sediments from the 15 boiler.

My invention further relates to provision of means for removing the mud or sediment from the mud drum.

My invention also comprehends certain 20 details of construction for improving the general efficiency of mud drums and parts associated therewith.

Reference is made to the accompanying 25 drawings forming a part of this specification and in which like letters indicate like parts.

Figure 1 is a fragmentary view partly in side elevation and partly in section showing a portable boiler used in connection with my improved mud drum. Fig. 2 is a section on 30 the line 2—2 of Fig. 1 looking in the direction of the arrow. Fig. 3 is a central vertical section through the mud drum. Fig. 4 is a vertical section on the line 4—4 of Fig. 3 looking in the direction of the arrow. Fig. 35 5 is a section somewhat similar to Fig. 4, but showing certain movable parts as occupying different positions from those indicated in Fig. 4. Fig. 6 is a detail showing in perspective one of the baffle plates carried by 40 the revoluble shaft.

A boiler shell is shown at 7 and a steam dome at 8. Located within the boiler shell are boiler flues 9. The inner wall of the fire box is shown at 10, and the outer wall of the 45 same at 11, there being between these two walls a water space 12. This water space communicates with the general water space 13 of the boiler.

My improved mud drum is shown at 14, 50 and may be conveniently located at one side of the fire box. A mud ring is shown at 15 and encircles the lowest portion of the boiler, and communicates therewith by a number of necks 16. The mud ring is connected by 55 another neck 17 with a valve 18, the latter

being connected by a neck 19 with the mud drum 14, as will be understood from Fig. 1.

The mud drum 14 carries two discharge valves 20, 21, which may be adjusted with great accuracy so as to permit a trivial escape of steam or water. The mud drum is further provided with two hand operated valves 22, 23, for discharging mud, sediment and water.

A revoluble shaft 24 threaded externally 65 is located axially within the mud drum 14, and at one of its ends engages a bearing 25, while adjacent its opposite end it extends through a stuffing box 26 and is provided with a hand crank 27. The shaft 24 70 carries a number of baffle plates 28 secured upon it by aid of its threaded surface. Each baffle plate 28 is provided with two lips 29, 31, and with a hole 30, this hole facilitating the introduction of the shaft 24 through the 75 baffle plates.

A quantity of mud or sediment, accumulated within the drum 14, is shown at 32. Grate bars are shown at 33, 34, the grate bar 33 being a plane bar and the bars 34 being 80 of articulate construction.

The operation of my device is as follows:—The parts being assembled and arranged as described, and steam being generated in the boiler, the mud and sediment 85 of the water tends to settle in the lowermost portion of the boiler. If, now, the valves 20, 21, be vented slightly so as to permit a slow escape of water, a current or draft of water is thus set up from the lower portion of the 90 boiler into the drum, and this insures the removal of sediment and mud from the boiler, and its deposit within the drum. The lips 29 serve to promote equal distribution 95 of the mud or sediment as deposited within the drum, as may be understood from Fig. 3. The operator by grasping the hand crank 27 and rotating the shaft 24, causes the baffle plates 28 to stir the mass of mud or sediment 32, and by aid of the hot water 100 within the mud drum, the mass of material 32 is soon rendered fluent, if it is not already so. This being done, the hand crank 27, is left in such position (see Fig. 5) that the lips 29 of the baffles 28 extend downwardly. There is now a clear space underneath the baffles 28 from one end of the drum to the other. The valves 22, 23, being now 105 opened, all mud and sediment is forced outwardly through these valves. I find that 110

comparatively little outflow of water through the valves 20, 21 is sufficient to promote enough draft or current to continuously remove the sediment or mud from the boiler into the mud drum. In fact, valves 20, 21, need not be opened except in the sense that they promote slow leakage. The waste of hot water from this case, therefore, becomes negligible. By use of the baffle plates 28, the deposit within the mud valve is distributed equally throughout the length of the mud drum. Except for the baffle plates, there would be a tendency for the material to accumulate at the ends of the mud drum, and by doing this the valves 20, 21, might become more or less obstructed. The shape of the lips 31 causes the material to be thoroughly stirred up when the shaft is rotated and the form of the lips 29, as indicated, is to control the distribution or equalize the quantities of the mud or sediment as deposited.

I do not limit myself to the precise arrangement shown, as variations may be made therein without departing from the spirit of my invention.

I claim:—

1. A device of the character described comprising a boiler, a mud ring communicating therewith, a mud drum connected with said mud ring for receiving mud therefrom, means for venting said mud drum in order to convey into said mud drum material deposited in said mud ring, and means for opening said drum in order to discharge said material therefrom.

2. In a mud drum the combination of a hollow member provided with discharge valves for water, and also discharge valves for mud or sediment, a revoluble shaft extending into said hollow member, and baffle plates mounted upon said revoluble shaft

and movable relatively to said hollow member.

3. The combination of a mud drum having the general form of a longitudinal cylinder, a pipe connected with said cylinder midway between the ends thereof in order to deliver into said mud drum deposits of mud or sediment, a plurality of baffle plates located within said drum, each plate provided with a lip bent to an angle relatively to the general axis of said drum, the baffle plates in half of said cylinder having their said lips bent in one direction and the baffle plates in the other half of said cylinder having their said lips bent in another direction for the purpose of promoting equality of distribution of material deposited within said cylinder, means for venting said cylinder in order to draw thereinto material precipitated in a boiler, and means for opening said cylinder in order to discharge said material.

4. A mud drum comprising a longitudinal hollow member having the general form of a cylinder, a revoluble shaft extending axially into said hollow member, a plurality of baffle plates mounted upon said revoluble shaft, each baffle plate being provided with a lip having a comparatively straight edge, said baffle plates being so arranged that the straight edges of said lips are arranged substantially in a common plane so that when said shaft is turned into a predetermined angular position, a clear space will be formed at the bottom of said cylinder, and means for venting said cylinder at the bottom thereof in order to discharge material deposited within said space.

ALEXANDER FRANKLIN SHREVE.
